UNITED STATES PATENT OFFICE.

AUGUST WILHELM MATTHAEI, OF BERLIN, GERMANY, ADMINISTRATOR OF
JENS RICHTER, DECEASED.

REPEATING-WATCH.

SPECIFICATION forming part of Letters Patent No. 430,739, dated June 24, 1890.

Application filed February 6, 1890. Serial No. 339,439. (No model.) Patented in Germany July 19, 1889, No. 50,669; in Belgium July 19, 1889, No. 87,047; in France July 19, 1889, No. 199,680; in England July 19, 1889, No. 11,561; in Switzerland July 20, 1889, No. 1,223; in Italy September 30, 1889, No. 25,969, and in Austria-Hungary February 2, 1890, No. 31,554 and No. 62,415.

To all whom it may concern:

Be it known that JENS RICHTER, deceased, a subject of the King of Denmark, and last residing in the city of Hong-Kong, a British Colony in Asia, did invent certain new and useful Improvements in Repeating Mechanism for Watches; and I, AUGUST WILHELM MATTHAEI, a subject of the Emperor of Germany, and a resident of the city of Berlin, in the German Empire, at present residing in the city of Washington, District of Columbia, United States of America, administrator of the estate of the said JENS RICHTER, do hereby declare that the said invention was patented in Germany under date of July 19, 1889, No. 50,669; in Belgium, dated July 19, 1889, No. 87,047; in France, dated July 19, 1889, No. 199,680; in England, dated July 19, 1889, No. 11,561; in Italy, dated September 30, 1889, Nos. 25,969 and 185; in Austria-Hungary, dated February 2, 1890, No. 31,554 and No. 62,415, and in Switzerland, dated July 20, 1889, No. 1,223, and that the following is a full, clear, and exact description of the invention of the said JENS RICHTER, which will enable others skilled in the art to which it appertains to make and use the same, reference being had to the accompanying drawings, and to letters and figures of reference marked thereon.

Referring to the drawings, Figure 1 is a face view of a watch, illustrating the repeating mechanism in its initial position or at its starting-point. Fig. 2 is a like view showing the position of the repeating mechanism after repeating the hour. Fig. 3 is a like view showing the position of the repeating mechanism after repeating the three-quarter hour. Figs. 4, 5, and 6 are face views of the repeating mechanism, the dial, the minute-hand, and the push-pins being indicated by dotted lines, showing the position of the repeating mechanism after repeating the twelfth hour and after repeating the first quarter and the half hour, respectively. Figs. 7, 8, 9, and 10 are face views of the several toothed wheels employed in the repeating mechanism. Fig. 11 is a side elevation of the watch, the repeat-

ing mechanism being shown in axial section. Fig. 12 is a similar view of the toothed wheels of the repeating mechanism detached, and 50 Fig. 13 is a sectional view showing the locking-pin at the starting-point of the repeating mechanism. Fig. 14 is a transverse section of the repeating mechanism on the line of pinion P. Fig. 15 is a perspective sectional 55 view thereof. Fig. 16 is a like view, a portion of the bridge B being broken away to show the pin that moves the pawl or lever L into engagement with the ratchet-ring R. Fig. 17 is an under side view of a portion of 60 the ratchet-ring R and the repeating-ring R³, showing the lever or pawl L connected with the latter ring; and Fig. 18 is a perspective view of the hour-hand with its arm L², that moves the stop-lever L into engagement with 65 the teeth of the ratchet-ring R³.

The invention relates to that class of watches known as "repeating-watches," in which the time is indicated either audibly or through the sense of feeling. In watches of 70 this character the time is usually conveyed by sound—that is to say, the watch is provided with a striking mechanism adapted to repeat the hour or a fraction of an hour. This requires a complicated and delicate 75 mechanism that is very expensive and liable to get out of repair. For the use of the blind watches have been provided with a dial having the hour numerals in relief to enable them to ascertain the time through the sense 80 of feeling or touch. This, however, requires considerable experience and delicacy of touch in order not to move the hands of the watch, while it necessitates the opening of the watch-case or glass face, which is undesirable. 85

This invention has for its object to provide a simple, strong, and efficient mechanism for repeating the hours and quarter-hours entirely independent of the watch-movement itself in its operation, as well as its location 90 relatively to said movement, and so constructed as that the desired information may be conveyed by impulses or shocks to the hand through the medium of a button and pin, or

a pin only, so that the watch need not be opened.

To these ends the invention consists in a repeating mechanism adapted to reciprocate 5 or vibrate a finger-piece, whereby distinct shocks or impulses are conveyed to the finger applied to such finger-piece, the number of shocks or impulses so conveyed indicating the time.

10 The invention further consists in the construction and combination of parts or elements and in their co-operation to produce the desired results, as will now be fully described.

15 In the drawings it is not deemed necessary to show the train of gearing or watch-movement, as this has no connection whatever with the repeating mechanism and forms no part of this invention, nor does it co-operate in any 20 manner with said repeating mechanism, which may therefore be used in conjunction with any watch-movement.

To the upper plate of the watch-movement, or to the dial-plate, is secured a ratchet-wheel 25 R, that is provided internally with forty-eight ratchet-teeth r. The wheel R is constructed with an annular flange r¹⁰, by means of which it is secured to the top plate of the watch-movement, and with a cylindrical portion r²⁰, that 30 has the ratchet-teeth r projecting horizontally and inwardly therefrom, the said teeth having their points in a direction the reverse of that in which the hour and minute hands move. On the wheel R are loosely mounted three 35 toothed wheels R' R² R³, the said wheels being rigidly connected together. The lower wheel R' is an ordinary gear-wheel, which may be provided with any desired number of teeth r', and serves to revolve the other two wheels, 40 there being a pinion P arranged to gear with the teeth of said wheel R', the spindle p of said pinion projecting through the watch-case C and carrying a button p' for revolving the same. The intermediate wheel R² has twelve 45 ratchet-teeth r², whose points lie also in a direction opposite to that of the motion of the hands H and H' and serve to repeat the hours. Finally, the top wheel R³ has thirty- 50 six ratchet-teeth r³, whose points lie in the direction of motion of the hands H and H'. The teeth r³ on wheel R³ are arranged in sets of three teeth, there being a notch or recess between each of said sets of three teeth, the recesses being numbered from 1 55 to 12, respectively. This wheel R³ serves to repeat the quarter-hours. The two wheels R² and R³ are so connected together as that each set of three teeth and a locking-notch of wheel R³ will lie over one of the teeth on 60 wheel R², as shown.

From what has been said it will be borne in mind that the wheels R and R² have their teeth arranged to point in the same direction—namely, in the direction of motion of 65 the hands of the watch—while the wheel R³ has its teeth arranged to point in a reverse direction, so that in repeating the hours the

wheel R³ has to be turned in the direction of motion of the hands, and when repeating the quarter-hours the wheel R³ has to be turned 70 in a reverse direction.

In order to communicate a shock to the finger to indicate the hour or portion thereof, I provide two pins P² and P³, that are adapted to co-operate with the wheels R² and R³, respectively. These pins move in sleeve-bearings p² and p³ on the watch-case, from which bearings they project sufficiently, so that they may be pushed inwardly into engagement with the teeth of wheels R² R³ and the recesses between each set of teeth of the last-named wheel. When either of the pins P² or P³ is depressed and again released, it is returned into its normal position by means of a spring secured in proper position within the 80 watch-case C, and whose free end engages the said pin. In Figs. 1, 2, and 3 these springs are shown in dotted lines, the spring s² operating the pin P², and the spring s³ the pin P³.

The wheel R³ has an enlargement r¹³, to the under side of which is pivoted at r²³ a lever or pawl L, that is held in a normal position by means of a spring S, secured to the enlargement, and whose free end engages a pin l' or stud on said pawl. The pawl L is provided 95 with a second pin l, that projects into a segmental slot r¹³, formed in the enlargement r¹³ of wheel R³, the said slot being a segment of a circle having the pawl-fulcrum r²³ for center, and is designed to limit the amplitude of motion of said pawl. As stated, the pawl L is fulcrumed to the under side of the enlargement r¹³ of wheel R³, so as to lie in the plane of the teeth r of the fixed ratchet-wheel R, and so as to engage the said teeth whenever moved 100 against the stress of its spring S. To the enlargement r¹³ is secured a bridge B, that covers the slot r¹³ and the pin l of pawl L projecting therethrough. The wing b of the bridge, that points in a direction the reverse 110 of that in which the hands move, is bent downward, so as to allow a more or less elastic arm L², secured to and revolving with the hour-hand H, to pass onto and over the bridge. The other wing b' of the said bridge is not 115 bent downwardly, so that the said arm L² may pass under the bridge and engage the pin l to move the pawl L into engagement with the teeth r of ratchet-wheel R whenever the wheels R² R³ are revolved in the direction of 120 motion of the hands of the watch.

In the upper plate of the watch-movement is arranged a spring-actuated pin P⁴, (shown in Figs. 11 and 13,) said pin being adapted to engage a hole r²¹ in the toothed wheel R', as shown, the upper end of said pin being beveled, so as to adapt the wheels to be turned in one direction, but to be locked against revolution in a reverse direction whenever the said pin is in engagement with the hole 130 r²¹ in said wheel R'.

The operation of the described repeating mechanism is as follows, it being borne in mind that whenever it is desired to ascertain

the time the repeating mechanism has to be brought to an initial or starting point, which is the pin P^4 , and that in doing this the said repeating mechanism has to be revolved in a direction opposite to that of the revolution of the hands of the watch. The pin P^4 is shown as located on a central line passing through the sixty and thirty minute graduations beyond the former graduation or above twelve o'clock, though it may be located at any other desired point, and the bevel of the pin is in the direction of motion of the hands of the watch. It is obvious, therefore, that whenever the repeating mechanism is brought to its starting-point it is locked against further rotation in the direction it was moved, thereby indicating to the manipulator that the said mechanism is in position for operation. As the bevel of the pin is in the direction of motion of the hands, the repeating mechanism is therefore free to revolve in that direction.

In Figs. 1 and 4 the repeating mechanism is shown in its initial position or at its starting-point, and in said Fig. 4 the watch indicates twelve o'clock, the notch 11 of toothed wheel R^3 lying opposite the push-pin P^3 .

To ascertain the time, the push-pin P^2 is pushed inwardly onto the periphery of the hour-repeating wheel R^2 . By revolving the repeating mechanism through the medium of the pinion P and the toothed wheel R' in the direction of motion of the hands the repeating mechanism is brought nearly back to its starting-point, the wing b' of bridge B will pass over the arm L^2 , and said arm will strike the pin l of pawl L , thereby moving the said pawl against the stress of its spring S into engagement with one of the teeth of the ratchet-wheel R , and simultaneously therewith the pin P^4 will snap into the hole r^2 of the toothed wheel R' , the pawl L locking the repeating mechanism against further motion. In this operation the repeating mechanism has made a complete revolution, during which the twelve teeth of wheel R^2 passed under pin P^2 , thereby imparting to said pin, and through the latter to the finger 12, impulses indicating the hour to be twelve o'clock. In order to verify the time indicated, the push-pin P^3 is depressed to repeat the quarter-hours.

It has hereinbefore been stated that in order to ascertain the quarter-hour the repeating mechanism is revolved in a direction opposite to that of the hands of the watch, the teeth on wheel R^3 pointing in the direction of motion of said hands; but since the notch 11 in said wheel R^3 has again been brought opposite to the pin-push P^3 when said pin is depressed it will enter the said notch 11 and lock the repeating mechanism against rotation in the stated direction. On the other hand, since the bevel of pin P^4 is in the direction of motion of the hands of the watch, this pin will also lock the repeating mechanism against motion in an opposite direc-

tion, thus verifying the time repeated. This hour can be repeated once only between the hours of twelve and one o'clock, and during this hour the starting-point will represent the twelfth hour. The reason why this hour can be repeated but once is that the bridge B would pass over arm L after said arm is carried beyond twelve o'clock and throw it into engagement with the ratchet-wheel R ; nor is the quarter-hour pin P^3 actuated between twelve o'clock and a quarter past twelve, for the reason that three teeth r^3 and a notch on wheel R^3 occupy a space equal to one tooth on the hour-repeating wheel R^2 . Hence during this time a notch will be opposite the push-pin P^3 ; but after a quarter past twelve the first quarter-hour can be ascertained by first revolving the repeating mechanism in the direction of motion of the hands of the watch, which will bring the last tooth of the three between notches 10 and 11 opposite pin P^3 , and by depressing the pin onto the wheel R^3 and revolving the repeating mechanism back again the said pin P^3 will ride over said last tooth and enter notch 11, thus producing one shock and locking the repeating mechanism against further motion.

In Figs. 5 and 6 the repeating mechanism is shown in its position before it is revolved back to indicate the quarter and the half hour, the push-pin P^3 in Fig. 5 being in contact with the first and in Fig. 6 with the second tooth of the set between the notches 10 and 11, so that if moved back one impulse will be imparted to the push-pin Fig. 5 and two impulses to the push-pin Fig. 6, indicating the quarter and half hours, respectively.

In Fig. 2 the repeating mechanism is shown in its position immediately after the repetition of the hour, (five o'clock,) said mechanism being shown as locked by pawl L .

In Fig. 3 the repeating mechanism is shown in its position after repeating the three-quarter hour, the hour being one-quarter to six o'clock, or five hours and three-quarters.

It will be seen that the repeating mechanism, irrespective of its being absolutely independent of the going-train, is extremely simple and can be made comparatively strong, occupying but little space.

In view of the fact that the said repeating mechanism is located above the going-train toothed disks may be used instead of wheels, as described, and said disks may be arranged to revolve on a hub, through which pass the hour and minute hand arbors. The arm L^2 , instead of being secured directly to the hour-hand, may be secured to bearing-sleeve thereof.

Having described the invention, what is claimed is—

1. In a repeating mechanism for watches, a wheel provided with a given number of teeth and adapted to revolve in a given direction from a predetermined starting-point and gearing adapted to revolve the wheel, in combination with a lock controlled by a mov-

ing element of the watch and adapted to lock said wheel against revolution and a push-pin adapted to bear on the periphery of the wheel, as and for the purpose set forth.

- 5 2. In a repeating mechanism for watches, a wheel provided with a given number of teeth and adapted to revolve in a given direction from a predetermined starting-point and gearing adapted to revolve the wheel, the 10 spindle of one of the gear-wheels being provided with a button for revolving the same, in combination with one of the hands of the watch, a lock controlled by said hand and adapted to lock the wheel against revolution, 15 and a push-pin adapted to bear against the periphery of the wheel, as and for the purposes set forth.

3. In a repeating mechanism for watches, a wheel provided with twelve ratchet-teeth 20 and adapted to revolve in a given direction from a predetermined starting-point, a spring-actuated pawl pivoted to said wheel, a fixed ratchet adapted to be engaged by the pawl to lock the wheel against revolution, and gearing adapted to revolve the wheel to and from 25 its starting-point, in combination with the hour-hand, an arm connected therewith and adapted to engage the pawl and move it against the stress of its spring into engagement with the teeth of the fixed ratchet, and 30 a push-pin adapted to bear against the periphery of the wheel, substantially as and for the purposes specified.

4. In a repeating mechanism for watches, 35 the wheel R^2 , provided with twelve teeth, the pawl L , pivoted to said wheel and having a pin l projecting through a slot in the wheel, and the bridge B on said wheel, overhanging the pin l , said bridge having wings b and b' , 40 arranged as described, and a fixed ratchet R , adapted to be engaged by the pawl L , in combination with the spring-actuated pin P^4 , bevelled as described, the gear-wheel R' , rigidly connected with wheel R^2 and having a hole 45 adapted to be engaged by the pin P^1 , the pinion P in gear with wheel R' , the hour-hand, the arm L^2 connected therewith and adapted to engage the pin l on pawl L , and a push-pin adapted to bear on the periphery of wheel 50 R^2 , substantially as and for the purposes specified.

5. In a repeating mechanism for watches, a wheel provided with thirty-six teeth ar-

ranged in sets of three teeth and a recess or notch between each set, said wheel being 55 adapted to revolve in a given direction from a starting-point, in combination with a push-pin adapted to be brought into engagement with the teeth and notches of said wheel, substantially as and for the purposes specified.

6. In a repeating mechanism for watches, a quarter-hour repeating-wheel provided with thirty-six teeth and a notch or recess between each set of three teeth, an hour repeating-wheel provided with twelve teeth, the teeth on said wheels pointing in opposite directions, a pawl pivoted to the quarter-hour repeating-wheel, a gear-wheel connected with the quarter-hour and hour repeating-wheels, a driving-pinion in gear with the gear-wheel, and a fixed ratchet adapted to be engaged by the pawl on the quarter-hour repeating-wheel, in combination with a lock adapted to lock the gear and repeating wheels 75 against revolution in one direction, the hour-hand of the watch, an arm controlled thereby and adapted to control the pawl to move the same into engagement with the fixed ratchet, and two push-pins adapted to be moved in contact with the teeth on the quarter-hour and hour repeating-wheels, respectively, substantially as and for the purposes specified.

7. The combination, with the ratchet-wheel R , the push-pins P^2 and P^3 , and the hour-hand carrying the arm L^2 , of the gear-wheel R' , its pinion P , the superposed toothed wheels R^2 R^3 , rigidly connected with the gear-wheel and arranged to revolve about the fixed ratchet R , the spring-actuated pawl L , provided with the pin l , projecting through a slot in wheel R^3 , to which said pawl is pivoted, and adapted to engage the teeth of the fixed ratchet, and the bridge B on wheel R^3 , having the wings b and b' and overhanging the pin l , said parts being arranged and operating substantially as and for the purposes specified.

In testimony whereof I affix my signature in presence of two witnesses.

AUGUST WILHELM MATTIAEI,
Administrator of the estate of Jens Richter, deceased.
